UNITED STATES PATENT OFFICE.

JOHN W. SMALL, OF WASHINGTON, DISTRICT OF COLUMBIA, AND LEWIS DE WITT FREEMAN, OF PORTSMOUTH, VIRGINIA.

LOCOMOTIVE.

Application filed December 3, 1920. Serial No. 428,040.

To all whom it may concern:

Be it known that we, JOHN W. SMALL and LEWIS DE WITT FREEMAN, citizens of the United States, residing at Washington,

5 District of Columbia, and Portsmouth, in the county of Norfolk and State of Virginia, respectively, have invented certain new and useful Improvements in Locomotives, of which the following is a specification.

10 This invention relates to an improved locomotive and has as one of its principal objects to provide an engine of this character employing separate steam and exhaust 15 valves and wherein the steam valves may be controlled independently of the exhaust valves.

The invention has as a further object, in thus employing separate controls for the 20 steam and exhaust valves, to provide an engine wherein the admission and cut-off of steam may be varied without varying the compression and release of steam so as to effect, as compared with locomotives of ordinary construction, a material reduction in 25 the steam clearance space necessary in the locomotive cylinders.

A still further object of the invention is to provide an engine wherein, due to the 30 conservation of steam by a reduction of the steam clearance space of the engine cylinders, more work will, as compared with engines of ordinary construction, be realized from a given volume of steam or, in other 35 words, less steam will be required to perform the same work.

Another object of the invention is to provide an engine wherein the valves will be operated by a valve gear common to all 40 thereof, wherein the valves will be mounted in removable cylinder heads so that repairs may be easily made, and wherein, if desired, the valves may be displaced without removing the heads.

45 And the invention has as a still further object to provide an engine wherein the saddle and cylinders will be formed without ports or passages so that the saddle and cylinders may thus be integrally cast and the 50 weight thereof thereby materially reduced as well as the presence of bolted joints eliminated.

Other and incidental objects will appear hereinafter.

In the drawings:

55 Figure 1 is a side elevation showing a locomotive embodying the present invention.

Figure 2 is a fragmentary transverse section particularly showing the saddle and illustrating the integral construction of the saddle and cylinders,

60 Figure 3 is a detail side elevation of the saddle,

Figure 4 is a detail side elevation of one of the cylinders and associated parts,

65 Figure 5 is a detail plan view of one of the cylinders, parts being broken away and shown in section to illustrate the mounting of the valves,

70 Figure 6 is a detail section of all of the valves of one of the cylinders,

Figure 7 is a perspective view showing one of the steam valves in detail,

75 Figure 8 is a fragmentary side elevation particularly showing the valve gear as well as the controlling mechanism for the valves,

Figure 9 is a detail perspective particularly showing the rock shafts of the valve gear,

80 Figure 10 is a detail perspective view showing one of the compound reverse links employed,

Figure 11 is a detail perspective view showing one of the link members of the compound reverse links,

85 Figure 12 is an edge elevation of the exhaust valve control lever,

Figure 13 is a side elevation of said lever,

Figure 14 is a side elevation of the steam valve control lever, and

90 Figure 15 is a fragmentary edge elevation showing both of the levers as they appear when mounted in operative position.

95 The present invention has to do particularly with the locomotive saddle, cylinders, valves, valve gear, and controlling mechanism for the valves. Accordingly, such parts of a locomotive, as illustrated in the drawings, which are not comprehended by the invention, are conventionally shown. In carrying the invention into effect, we provide, as will be best seen in Figures 2 and 3 of the drawings, a saddle 10 provided at its upper end with an arcuate plate 11 upon which the smoke box of the locomotive rests. Standing from the base of the saddle are flanges 12 to which the frame bars of the

locomotive are secured and carried by the saddle base at opposite sides thereof are cylinders 13 connected with the saddle by webs 14. As will be perceived, the saddle 5 and cylinders are thus constructed as a single unit and, as will later become more clear, are formed without ports or passages. Accordingly, the saddle and cylinders may be integrally cast. In thus casting the cylinders integral with the saddle, the weight 10 of the unit may be materially reduced while, also, the presence of troublesome bolted joints is eliminated. Bolted to the forward end of each of the cylinders is, as particularly shown in Figure 5, a removable front head 15 and similarly secured to the rear end of each of the cylinders is a removable back head 16. The front heads are respectively formed with a steam passage 17 and 20 an exhaust passage 18. Likewise, the back heads are each formed with a steam passage 19 and an exhaust passage 20. Emerging through the sides of the smoke box are steam pipes 21 each provided with branches 22, one of which is connected with the steam passage of the front head and the other with the steam passage of the back head of the cylinder at the adjacent side of the locomotive. Leading from the exhaust passages 30 of the heads of each cylinder are the branches 23 of an exhaust pipe 24, these pipes, as clearly brought out in Figure 2, extending laterally inward through suitable openings in the sides of the saddle 10. Detachably mounted upon the saddle plate 11 to extend upwardly therethrough into the smoke box of the locomotive is an exhaust nozzle 25 provided near its lower end with a flange 26 bolted or otherwise secured to the plate 11 and sustaining the nozzle thereon. Below this flange the nozzle is formed with oppositely directed branches 27 to which the pipes 24 are secured. Thus, provision is made for the admission and 45 exhaust of steam to and from the cylinder heads without the presence of ports or passages in the cylinders or in the saddle. Within the cylinders are liners 28 and slideable within said liners are the pistons 29 of the locomotive, these pistons having the usual piston rods 30 reciprocable through the back heads 16 of the cylinders between the passages 19 and 20 thereof. These heads 50 carry glands 31 for the piston rods and projecting rearwardly from each of the heads is a pair of vertically spaced lugs 32 to which the cross head guides are secured.

Traversing the passages 17 and 19 of the front and back heads of each of the cylinders are valve chambers 33 in which are removably mounted liners 34 each having, as particularly shown in Figures 5 and 6 of the drawings, a vertical inlet port 35 and a 60 pair of vertical outlet ports 36 communicating with passages 37 leading through the

heads into the ends of the cylinder. Traversing the passages 18 and 20 of the heads of each of the cylinders are valve chambers 38 in which are removably fitted liners 39 each having a pair of vertical inlet ports 70 40 and a single outlet port 41, these ports 41 being in communication with passages 42 leading through the heads into the ends of the cylinder. Rotatable within the liners 34 are vertically disposed steam valves 43 75 and rotatable within the liners 39 are similarly disposed exhaust valves 44. These valves are all quite similar in construction and in Figure 7 of the drawings, we have shown one of the steam valves in detail. As there illustrated, said valves each comprise spaced annular top and bottom heads 45 and 46 adapted to snugly fit within the liners of the valve chambers and connecting said heads is a pair of spaced vertical 80 webs, the webs of the steam valves being formed to cover and uncover the ports 36 while the webs of the exhaust valves are formed to cover and uncover the ports 40. Between the webs of each valve is defined 85 a steam passage. Detachably engaging with each of the valves is a stem 47 provided at its lower end with an annular head 48. This head is of a diameter corresponding to that of the valve heads respectively, and is provided upon its lower side with a transverse key 49 normally fitting in a transverse slot 50 formed in the upper face of the top head 45 of the valve for connecting the stem therewith. Closing the valve chambers at 90 their upper ends are bonnets 51 bolted or otherwise secured in position and rising from said bonnets are yokes 52 through which the stems 47 of the valves are journaled. Surrounding said stems upon the 95 bonnets are glands 53. Bolted to the cylinder heads and closing the valve chambers at their lower ends are bottom plates 54 against which the bottom heads 46 of the valves rest so that these plates thus 100 rotatably support the valves in position. Accordingly, as will be readily seen, the plates 54 may be removed when the valves may be withdrawn downwardly and displaced so that, without removing the cylinder 105 heads, access to the valves may be easily had. Similarly, the liners of the valve chambers may be removed. However, should it be desired to gain access to the cylinders, the cylinder heads may also be 110 readily detached.

Upstanding from each of the cylinders 13 medially thereof is a post 55 upon the upper end of which is journaled a rocker 56 having a pair of arms 57 and a third arm 58. Secured to the upper ends of the stems of the steam valves of the cylinder are arms 59 and extending between these arms and the arms 57 of the rocker are rods 60 coupling the steam valves of each cylinder to rotate 120 125 130

in unison. Secured to the upper ends of the stems of the exhaust valves of each cylinder are arms 61 and extending between these arms is a rod 62 coupling the exhaust valves 5 of the cylinders respectively to move in unison. Extending from each of the cross heads of the locomotive is an arm 63 upon which is mounted a link 64 and pivoted upon said link are upstanding levers 65 and 66 respectively. Extending between the arm 58 of the steam valve rockers 56 respectively and the lever 65 at each side of the locomotive is a coupling rod 67 and extending between the rearmost of the arms 61 of the exhaust valves at each side of the locomotive and a corresponding one of the levers 66 is a coupling rod 68. Mounted at each side of the locomotive is a compound reverse link 69 comprising, as particularly shown in Figure 10, a link member 70 and a second link member 71, the member 71 having a tail piece 72. Suitable spacing blocks are interposed between the link members and abutting the outer sides of said members 71 are cheek plates 73 having lateral supporting trunnions 74, bolts being engaged through the ends of said plates, the spacing blocks, and the end portions of the link members for holding the parts in assembled relation. Slidable within the arcuate slot of the link member 70 is a link block 75 and slidable within the slot of the link member 71 is a link block 76. Connected to the upper end of each of the levers 65 at opposite sides of the locomotive is a rod 77 provided at its rear end with a fork 78 straddling the corresponding link member 70 and pivotally connected to the block 75 thereof while to each of the levers 66 at opposite sides of the locomotive is connected a rod 79 provided at its rear end with a fork 80 straddling the corresponding link member 71 and pivotally connected to the block 76 thereof. Fixed to the main crank pins of the locomotive are crank arms 81 and extending between these arms and the tail pieces 72 of the reverse links are rods 82. Thus, as will be well understood, an oscillatory movement will be imparted to the reverse links and communicated through the rods 77 and 79 to the levers 65 and 66. This movement of said levers, in conjunction with the movement imparted thereto by the cross heads of the locomotive, will serve to rotate the steam and exhaust valves so that these valves will be properly opened and closed incident to the movement of the pistons of the engine cylinders. The travel of the valves will, of course, be determined by the distance of the link blocks of each of the reverse links from the pivotal axis thereof and it accordingly remains to describe the control mechanism provided for adjustably varying such distance and accordingly controlling the travel of the valves as well as the means employed for re-

versing the direction of movement of the locomotive.

Journaled beneath the locomotive boiler is, as illustrated in detail in Figure 9, a transverse rock shaft 83 and surrounding said shaft is a tubular shaft 84 journaled to rock about the former shaft. Fixed to one end portion of the shaft 83 is a crank arm 85 and fixed to the opposite end portion of said shaft is a compound crank having arms 86 and 87. Extending between the arms 85 and 86 and the forks 78 of the rods 77 at opposite sides of the locomotive, are links 88 and extending rearwardly from the arm 87 of the compound crank at the right hand side of the locomotive, is a reach rod 89 entering the locomotive cab. Fixed to one end of the tubular shaft 84 is a crank arm 90 and fixed to the opposite end of said shaft is a compound crank having arms 91 and 92 respectively. Extending between the arms 90 and 91 and the forks 80 of the rods 79 at opposite sides of the locomotive, are links 93, and extending rearwardly from the arm 92 of the compound crank is a reach rod 94 which, like the reach rod 89, enters the locomotive cab at the right hand side of the locomotive. Pivoted within the locomotive cab are, as particularly shown in Figures 12 to 15 inclusive, coacting steam and exhaust levers 95 and 96 which are mounted to rock about a common center, the rod 89 being connected to the lever 95 and the rod 94 to the lever 96. Each of said levers is provided with a yoke 97 and freely received through the yoke of the steam lever is a toothed segment 98 while the yoke of the exhaust lever receives a segment 99 therethrough, this latter segment being provided near one end, as particularly shown in Figure 8 of the drawings, with a notch 100 while near the opposite end of said segment is a second notch 101. Slidable within the yoke of the lever 95 is a latch block 102 spring pressed to engage the segment 98 and having a trigger 103 connected therewith for lifting the block. Connected to said block to extend laterally therefrom is a dog 104 provided at the inner side of the lever with a lug 105. Fixed to the lower end portion of the exhaust lever 96 is an arcuate stop bar 106 provided at its ends with laterally directed arms 107 and 108 projecting into the path of swinging movement of the lever 95. The lever 96 is also equipped with a latch block 109 slidable within the yoke 110 of said lever and spring pressed to engage the segment 99. Connected with said block is a trigger 110 by which the block may be lifted, and fixed to the block to project at the inner side of the lever is a cam member 111 having a head 112 provided with a convex upper face extending into the path of the lug 105 of the dog 104 of the lever 95 and provided with a notch 113 adapted to freely receive said lug.

As will now be appreciated in view of the preceding description, the steam lever 95 may be rocked for shifting the rear end portions of the rods 77 and adjustably positioning the link blocks 75 within the reverse links 69. Likewise, the lever 96 may be rocked for shifting the rear end portions of the rods 79 and adjustably positioning the link blocks 76 within said links. By swinging the lever 96 forwardly and engaging the latch block 109 thereof in the notch 100 of the segment 99, the locomotive will be caused to move forwardly while the link blocks 76 will be elevated to their uppermost positions within the reverse links 69 so that the exhaust valves 44 will have full travel. On the other hand, by swinging the lever 96 rearwardly and engaging the latch block thereof in the notch 101 of the segment 99, the locomotive will be caused to move rearwardly while the link blocks 76 will be shifted to their lowermost positions within the reverse links so that the exhaust valves will have full travel. Thus, without regard as to whether the locomotive is moving forwardly or backwardly, the exhaust valves will always have full travel. As best brought out in Figure 8, when the exhaust lever 96 occupies its forward position, the steam lever 95 may be adjusted forwardly between the arms 107 and 108 of the bar 106 for shifting the link blocks 75, as previously indicated, and accordingly varying the travel of the steam valves 43. Likewise, when the exhaust lever 96 occupies its rearward position, the steam lever may be adjusted rearwardly between the arms 107 and 108, for varying the travel of the steam valves. Accordingly, without regard to the direction of movement of the locomotive, the steam valves may be controlled independently of the exhaust valves so that the admission and cut-off of steam may be varied as desired without varying the compression and release of the steam.

The particular function of the dog 104, cam member 111, and bar 106 may now be made clear. Assuming that the levers 95 and 96 have, as shown in Figure 8, been moved to each occupy a forward position and the lever 96 is, without first shifting the steam lever 95, moved rearwardly for reversing the direction of movement of the locomotive, it will be seen that the head 112 of the cam member 111 will ride beneath the lug 105 of the dog 104 for lifting the latch block 102 and releasing the lever 95, the lug of the dog engaging in the notch 113 of the head of the cam member for coupling the levers. Consequently, as the rearward swinging movement of the lever 96 is continued, the steam lever will be swung therewith. A similar result would, of course, ensue should the exhaust lever be swung forwardly from its rearmost position without first swinging the steam lever. In the for-

ward position of the exhaust lever, the arm 108 of the bar 106 will, as best brought out in Figure 8, limit the steam lever against rearward adjustment beyond vertical position while, when the exhaust lever occupies its rearward position, the steam lever will be limited by the arm 107 against forward adjustment beyond vertical position. The arms 107 and 108 will, therefore, serve to define the limits of the movement of the steam lever with respect to the exhaust lever, making it impossible to improperly manipulate said levers so as to oppose the movement of the steam valves with respect to the movement of the exhaust valves.

Having thus described the invention, what is claimed as new is:

1. In a locomotive, a working cylinder, separate admission and exhaust valves therefor, means for imparting travel to the valves, means for reversing travel of the admission valves, and means for reversing travel of the exhaust valves and operable to coact with said second mentioned means for automatically reversing the travel of the admission valves coincidently.

2. In a locomotive, a working cylinder, separate admission and exhaust valves therefor, means for imparting travel to the valves, means for reversing travel of the admission valves and adjustable for varying said travel, means for reversing travel of the exhaust valves, and means limiting said second mentioned means whereby to prevent independent reversal of travel of the admission valves.

3. In a locomotive, a working cylinder, separate admission and exhaust valves therefor, means for imparting travel to the valves, a lever for reversing travel of the admission valves, a lever for reversing travel of the exhaust valves, and coacting means carried by said levers whereby movement of the second lever for reversing travel of the exhaust valves will effect movement of the first lever for reversing travel of the admission valves.

4. In a locomotive, a working cylinder, separate admission and exhaust valves therefor, means for imparting travel to the valves, a lever for reversing travel of the admission valves, a lever for reversing travel of the exhaust valves, and coacting means carried by the levers whereby movement of the second lever will effect movement of the first lever in the same direction.

5. In a locomotive, a working cylinder, separate admission and exhaust valves therefor, means for imparting travel to the valves, a lever for reversing travel of the admission valves and adjustable for varying said travel, a second lever for reversing travel of the exhaust valves, and a bar carried by the second lever and having arms limiting the first lever whereby to prevent

- independent reversal of travel of the admission valves.
6. In a locomotive, a working cylinder, separate admission and exhaust valves there-
5 for, means for imparting travel to the valves, pivoted levers adjustable for revers-
ing travel of the admission and exhaust valves respectively, means carried by each of the levers for locking said levers in ad-
10 justed position, and coacting means carried by the levers for releasing the locking means of one of the levers and coupling the levers when the other lever is swung.
7. In a locomotive, a working cylinder, separate admission and exhaust valves there-
15 for, means for imparting travel to the valves, pivoted levers adjustable for revers-
ing travel of the admission and exhaust valves respectively, a latch carried by each of the levers for locking said levers in adjusted position, a dog carried by the latch of one of the levers, and a cam member carried by the latch of the other lever and adapted to ride beneath said dog
- for elevating said latch, said cam member 25 being provided with a notch for receiving the dog whereby to couple the levers when the latter lever is swung.
8. In a locomotive, a working cylinder, ad-
mission and exhaust valves therefor, a com-
pound reverse link having link members, link blocks slidable upon said members, sepa-
rate connections between said blocks and the admission and exhaust valves respectively including rods having forks straddling the 30 link members and pivotally connected to said blocks, a pair of rock shafts one ex-
tending through the other, arms carried by said shafts, links pivotally secured between the free ends of said forks and connected to 35 said arms, and a pair of levers operatively connected with said shafts and movable for rocking the shafts independently of each other.

In testimony whereof we affix our signa- 45 tures.

JOHN W. SMALL. [L.S.]

LEWIS DE WITT FREEMAN. [L.S.]
